BOARD DROP HAMMER

Filed July 15, 1926

UNITED STATES PATENT OFFICE

MORTON C. TALCOTT, OF HARTFORD, CONNECTICUT, ASSIGNEE TO THE BILLINGS & SPENCER COMPANY, OF HARTFORD, CONNECTICUT, A CORPORATION OF CONNECTICUT

BOARD DROP HAMMER

Application filed July 15, 1926. Serial No. 122,556.

The invention consists in the organization of means controlling the lifting rolls in board drop hammers having more than two pairs of lifting rolls and its object is to provide simple mechanism whereby such rolls may be simultaneously and equally moved into gripping relation with the hammer-board and simultaneously and positively withdrawn therefrom as hereinafter more fully explained in conjunction with the accompanying drawing.

In said drawing, Fig. 1 is a vertical front elevation of a three roll-set board drop hammer.

Fig. 2 a larger scale side elevation, partly in section, and

Fig. 3 a horizontal section taken just above the intermediate roll set.

The machine, as shown in Fig. 1, comprises a base 1, two uprights 2 in which the hammer 3 is guided and a head structure in which the several sets or pairs of rolls are mounted. The rear rolls of all the sets are marked 5 and each is fixed on an axle 6, which is journaled at its ends in eccentric sleeve bearings 7, the latter being journalled directly in the head frame. Each eccentric bearing sleeve 7 is provided with a rearwardly extending arm 8 at each end and the two arms pertinent to each roll are rigidly joined together by a cross pin 9, Fig. 2. All the cross pins 9 are rigidly connected together and to an adjustment rod 10, which is secured to the frame with suitable provisions for its longitudinal adjustment. It will be understood that this adjustment simultaneously and equally rocks all of the arms 8 and eccentric bearings 7, thereby causing the rear rolls 5 to be equally and simultaneously advanced or withdrawn with reference to the plane of the hammer-board 3a, as will be understood.

The several front rolls are marked 11, 12 and 13 respectively and each is similarly fixed to an axle 6 and the latter are journalled in eccentric bearings or sleeve 7, which sleeves are journalled in the head frame. These eccentric sleeve bearings are also provided with arms, projecting forwardly and marked 14, 15 and 16 respectively, the two arms pertinent to each roll being joined by cross pins 17, 18

and 19 respectively. The cross pins are shown as clamped in the split ends of such arms, which forms a rigid connection between the arms for each roll.

All the arms of the front rolls 11, 12 and 13 are connected to the friction bar 20 so that the latter may simultaneously move them and thereby cause their rolls to be advanced into pressing contact with the hammer-board and withdrawn therefrom. To this end the arms 15 and 16 of the lowest and intermediate front rolls are connected to each other by angularly related links, marked 21 and 22 respectively. These links normally occupy an angle to each other about as indicated in the drawing, and at their connected ends, they are pivoted to one end of a pressure distributing lever 23. The other end of this lever is connected by an upwardly extending link 24 to the cross pin 17 of the eccentric arms 14 of the upper front roll 11. The upper end of the friction bar 20 is connected to the distributing lever 23 at a point nearer to the end connected to the two rolls than to the other end and approximately so that the ratio of the lever arms is as 2 to 1.

The pressure-distributing system above described permits the roll arms 15 and 16 to move independently of each other, so that the weight of the friction bar transmitted to them through the distributing lever 23 is approximately equalized as between these two rolls. The other roll arms 14 also have freedom for movement independent of the arms 15 and 16. By virtue of the ratio of the arms of lever 23 approximately one-third of the weight of the friction bar is transmitted to the arms of the upper front roll 11, and two-thirds to the others. In this way all of the movable rolls of the three pairs of rolls are moved, by the weight of the friction bar, simultaneously into gripping relation to the hammer-board and into substantially equal frictional contact therewith, the roll arms 14, 15 and 16 being all of equal radius and the eccentricities of their several bearing sleeves being also equal and in the same direction. The actual movement of the rolls themselves toward the board is slight and when the friction bar is lifted, all of the rolls are withdrawn from the

board simultaneously. This is due, in part, to the fact that the greatest friction to be overcome, in such movement, is represented by the bearing surfaces of the several eccentric sleeves in the roll head frame, and to the angular relationship of the levers and links by which the roll arms are operated. As indicated in Fig. 1, the links 24, 21 and 22 are disposed in pairs, one member of each pair being on opposite sides of the distributing lever 23 and the jaw on the upper end of friction bar embraces the latter.

The several pairs of rolls may be rotated in any suitable way but preferably by means of two pulleys, one on either side of the machine, both on the same shaft, such as the middle roll shaft 6, which shaft is provided with spur gears 25 through which it drives the other rolls, through idlers 26, as will be plain in Fig. 2. It will be understood that the friction bar is guided in a box or casing, such as indicated at 27, containing a catch and a knock-off bolt adapted for operation by the inclined face 28 on the hammer 3. The catch in the box (not shown) holds the friction bar and its connected parts in an elevated position until the hammer descends and by its cam face 28 releases the catch. This allows the friction bar to fall, closing the three front rolls against the board and thereby lifting the hammer. In its upstroke a stud 29 on the hammer encounters a lever 30 connected to the friction bar, so as to raise the latter and thus open the rolls, allowing the hammer to drop again and repeat the cycle, thus producing sustained hammer reciprocation, until the hammer is retained in its elevated position by the operation of the board clamp, indicated at 31 (Fig. 2) which is of usual construction and need not be described; it is controlled as usual by a foot pedal 32 indicated in Fig. 1. It will be understood that the weight of the friction bar, in the present case, furnishes the pressure for engaging the rolls to the hammer-board, but that any other suitable hammer-controlled and pressure-exerting mechanism will produce the same effect so far as movement of the rolls is concerned.

What I claim is:

1. In a multiple roll-set board drop-hammer the combination of the movable rolls of each set, eccentric bearings therefor having actuating arms, a pressure distributing lever connected by one end to the arms of two of said rolls and by the other end to the arms of another roll and hammer-controlled pressure means connected to said lever.
2. In a multiple roll-set board drop-hammer, the combination of the movable rolls of each set, eccentric bearing sleeves therefor having actuating arms, a lever, means connecting the arms of two of said rolls to one end of said lever adapted to permit relative movement between said arms, the arms of the remaining roll being connected to the other

arm of said lever, and hammer-controlled mechanism adapted for operating said lever to produce sustained hammer reciprocation.

3. In a multiple roll-set board drop-hammer, the combination of the movable roll of each set, movable bearings therefor having actuating arms, a lever, angularly related links connecting one end of the arms of two of said rolls to one arm of said lever and adapted to permit independent movement of said arms, the other arm of said lever being connected to the actuating arm of another roll and a hammer-controlled friction bar connected to said lever at one side of the center thereof.

In testimony whereof, I have signed this specification:

MORTON C. TALCOTT.
